CLAIM

The ornamental design for a display screen or portion
thereof with icon, as shown and described.

DESCRIPTION

The sole FIGURE is a front view of a display screen or
portion thereof with icon showing our new design.

The innermost broken lines illustrate portions of a graphical
user interface and a display screen or portion thereof, and
form no part of the claimed design. The remaining broken

(Continued)

lines illustrate an electronic device, which is the environment of the design, and form no part of the claim.
